(57) **CLAIM**

The ornamental design for an LED array for use in a warning light, as shown and described.

DESCRIPTION

FIG. 1 is a perspective view of an LED array for use in a warning light in accordance with my Design;

FIG. 2 is a top view thereof, the LED array for use in a warning light appearing the same from the bottom;

FIG. 3 is a front view thereof;

FIG. 4 is a side view thereof, the LED array for use in a warning light appearing the same when viewed from the opposite side; and,

FIG. 5 is a rear view thereof, the rear view of my LED array for use in a warning light not encompassing any Design features.
